TELEPHONE LINE CIRCUIT

Morris E. Griffins, Riverside, Ill., assignor to Associated Electric Laboratories, Inc., Chicago, Ill., a corporation of Delaware

Application October 5, 1940, Serial No. 359,827

11. Claims. (Cl. 179—17)

The present invention relates to line circuits for automatic telephone systems and more particularly to improved line circuits of the general character disclosed in U. S. Patent No. 2,199,543, Clarence E. Lomax, granted May 7, 1940.

In the Lomax patent, an improved telephone line circuit for a subscriber line of the party type is disclosed, which is so connected and arranged that associated automatic switching apparatus is controllable to render by way of the subscriber line both calling and called services and also reverting call service, in spite of the fact that the line circuit comprises only two relays, a line relay and a cut-off relay.

While this line circuit is entirely satisfactory in operation and productive of a considerable reduction in manufacturing costs over conventional line circuits, it, in turn, is somewhat more expensive to manufacture than is desirable, due primarily to the provision of a mechanical interlock between the line relay and the cut-off relay embodied therein.

Accordingly, it is an object of the present invention to provide an improved telephone line circuit of the type described which comprises only a line relay and a cut-off relay, and which requires no mechanical interlock between the line relay and the cut-off relay.

Another object of the invention is to provide a telephone line circuit of the type described which embodies an improved and exceedingly simple circuit network.

The objects set forth above are attained in accordance with the present invention by providing a line circuit adapted for use in a telephone system including a subscriber line of the party type and automatic switching apparatus having access to the subscriber line; which line circuit consists solely of a line relay, a cut-off relay, the relays being mechanically operative entirely independently of each other, a control network for selectively operating the line relay and the cut-off relay, and control circuits for the switching apparatus governed by the line relay and the cut-off relay, whereby the switching apparatus is selectively controllable to render the substations on the subscriber line both calling and called services and also reverting call service.

More particularly, the control network for the line relay and the cut-off relay comprises a first operating circuit including a first winding of the line relay, a second operating circuit including in series a second winding of the line relay and a first winding of the cut-off relay, and third and fourth independent operating circuits each in-

cluding in series the first winding and a second winding of the cut-off relay. The control network is so connected and arranged that the first, second and third operating circuits are selectively controlled incident to rendering calling and called services over the subscriber line; while the fourth operating circuit is controlled incident to rendering reverting call service over the subscriber line and incident to locking the subscriber line out of service in the event a fault appears thereon.

Further features of the invention pertain to the particular arrangement of the circuit elements thereof, whereby the above-outlined and additional operating features are attained.

The novel features believed to be characteristic of the invention are set forth with particularity in the appended claims. The invention, both as to its organization and method of operation, together with further objects and advantages thereof, will best be understood by reference to the following specification taken in connection with the accompanying drawings, in which Figures 1 and 2 taken together illustrate diagrammatically a telephone system including a line circuit embodying the present invention.

Referring now more particularly to Figs. 1 and 2 of the drawings, the telephone system there illustrated comprises an exchange having a plurality of subscriber lines, including the subscriber lines 150 and 160, terminating thereat and provided with a plurality of finder-connector links, including the link 100, for setting up connections between the various subscriber lines. Also, a distributor 103 is provided for assigning idle ones of the links to the use of calling ones of the subscriber lines; and a number of reverting call switches, including the reverting call switch 200, are provided for the purpose of projecting code ringing current over a subscriber line when a reverting call is initiated thereon. More specifically, the exchange has an ultimate capacity of one hundred lines and the number of links is determined by the amount of traffic which the exchange is required to handle, usually ten links being adequate to render satisfactory service.

Each of the links may be identical to the link 100 which comprises a finder 101 and a connector 102, each having access to each subscriber line in the system. The finder and the connector included in the link may be of any of a number of well-known types. However, it is preferable that both the finder and the connector include a switching mechanism of the Strowger type and

the usual control apparatus therefor, the wipers of the switching mechanism included in the finder 101 being illustrated at 180, 181 and 182, and the wipers of the switching mechanism included in the connector 102 being illustrated at 183, 184 and 185. Also, the connector 102 comprises impulse-responsive apparatus of any desired type for projecting code ringing current over an idle called subscriber line after it has been seized by the switching mechanism included therein, which is so connected and arranged that a divided ringing circuit may be employed in the system. The distributor 103 may be of any of a well-known number of types. However, it is preferable that the distributor 103 is of the pre-selective type such that an idle link is selected to be assigned to the use of a calling subscriber line prior to the initiation of a call on the subscriber line.

At least a number of the subscriber lines terminating at the exchange are of the party type, the subscriber lines 150 and 160 being party subscriber lines, each serving a number of substations respectively including the substations A, B and C, D. Each of the substations is provided with a telephone instrument, a dial mechanism and a ringer. The substations associated with each party subscriber line are arranged in two groups, the ringer at each substation in the first group being connected between one line conductor of the subscriber line and ground, and the ringer at each substation in the second group being connected between the other line conductor of the subscriber line and ground, whereby a divided ringing circuit is employed in the system.

A line circuit is individually associated with each subscriber line in the system, the line circuit 104 being individually associated with the subscriber line 150 and the line circuit 105 being individually associated with the subscriber line 160. Each of the line circuits may be identical to the line circuits 104 and 105 which respectively comprise line relays R120 and R130 and cutoff relays R110 and R140.

Each of the reverting call switches may be identical to the reverting call switch 200 which comprises two minor switches 280 and 290, a line relay R230, a hold relay R240, two transfer relays R260 and R270, a ring cutoff relay R255, a switch-through relay R220, two control relays R210 and R250, the control and controlled circuits therefor, and a transformer 201. The minor switch 280 comprises two rotary wipers 283 and 285 provided with individually associated contact banks 284 and 286, respectively, a rotary magnet M236 for driving the wipers noted, and a release magnet M237 for releasing the wipers noted and for causing them to be returned to their normal positions. Also, a set of switch springs S234 is individually associated with the minor switch 280 and controlled by the operation of the wipers thereof away from their normal positions. Similarly, the minor switch 290 comprises two rotary wipers 293 and 295 provided with individually associated contact banks 294 and 296, respectively, a rotary magnet M238 for driving the wipers noted, and a release magnet M239 for releasing the wipers noted and for causing them to be returned to their normal positions. Also, a set of switch springs S235 is individually associated with the minor switch 290 and controlled by the operation of the wipers thereof away from their normal positions. Further it is noted that the reverting call switch 200

is connected and arranged to project code ringing current over a calling subscriber line by way of the trunk 170 when a connection is established therebetween by way of an operated one of the links, in such a manner that a divided ringing circuit is employed in the system.

The connection and arrangement of the system will best be understood from a consideration of the operation of the apparatus incorporated therein to set up the different connections between the various subscriber lines.

A call which is to be extended from the substation A to the substation C is first initiated at the substation A by removing the receiver of the telephone instrument thereat from its associated switchhook, thereby to complete a bridge path at the telephone instrument at the substation A between the line conductors C151 and C152 of the subscriber line 150 extending thereto. When this bridge path between the line conductors of the subscriber line 150 is completed, a bridge circuit is completed for energizing the upper winding of the line relay R120 in the line circuit 104 individually associated with the subscriber line 150. This bridge circuit extends from ground by way of the contacts 115 to the line conductor C152 of the subscriber line 150, and from battery by way of the upper winding of R120 and the contacts 111 to the line conductor C151 of the subscriber line 150, the line conductors C151 and C152 of the subscriber line 150 being connected together by way of the bridge path at the substation A. When thus energized, the line relay R120 operates to complete, at the contacts 123, a priming circuit for energizing in series the upper and lower windings of the cutoff relay R110, this circuit extending from ground by way of the lower winding of R110, the contacts 123, the resistor 128 and the upper winding of R110 to battery. When this priming circuit is thus completed the cutoff relay R110 does not operate due to the high series resistance of the resistor 128. Also, the line relay R120 completes, at the contacts 121, a path for applying battery potential to the control conductor C153 of the subscriber line 150, this path extending from battery by way of the upper winding of the cutoff relay R110, the lower winding of the line relay R120 and the contacts 121 to the control conductor C153. This application of battery potential to the control conductor C153 of the subscriber line 150 marks the rotary position of the contact set in the level in the contact bank of the Strowger mechanism included in the finder 101, wherein the calling subscriber line 150 terminates. Finally, the line relay R120 completes, at the contacts 127, an obvious path for applying ground potential to the start conductor C190 extending into the distributor 103. This application of ground potential to the start conductor C190 initiates the operation of the distributor 103 and causes the distributor to operate and assign the previously selected idle link to the use of the calling subscriber line 150. Assuming that the link 100 illustrated is assigned by the distributor 103 at this time, the distributor also marks with ground potential by way of the conductor C193 the level in the contact bank of the Strowger mechanism included in the finder 101, wherein the calling subscriber line 150 terminates.

The Strowger mechanism included in the finder 101 then operates to move the wipers 180, 181 and 182 thereof in the vertical direction to the level wherein the calling subscriber line 150 terminates. This Strowger mechanism then op-

erates to move the wipers thereof in the rotary direction to the rotary position of the contact set, wherein the calling subscriber line 150 terminates, at which time the wipers 180 and 182 thereof engage the contacts terminating the line conductors C151 and C152, respectively, of the subscriber line 150, and the wiper 181 thereof engages the contact terminating the control conductor C153 of the subscriber line 150. The presence of battery potential upon the control conductor C153 of the subscriber line 150 completes a circuit for energizing a relay in the finder 101, thereby to cause the last-mentioned relay to operate and arrest further operation of the Strowger mechanism included therein; whereupon apparatus in the finder 101 operates to complete a path for applying ground potential to the wiper 181. This application of ground potential to the wiper 181 completes a circuit for energizing in series the lower winding of the line relay R120 and the upper winding of the cutoff relay R110, this circuit extending from the grounded wiper 181 by way of C153, the contacts 121, the lower winding of R120 and the upper winding of R110 to battery. Also, this application of ground potential to the wiper 181 completes a path for applying ground potential to the control conductor C154 of the subscriber line 150 extending to the contact banks of the Strowger mechanisms included in the connectors of the links having access thereto, thereby to mark the subscriber line 150 as busy to the connectors of these links. This path extends from the grounded wiper 181 by way of C153, the contacts 121 and 125 to the control conductor C154.

When the lower winding of the line relay R120 and the upper winding of the cutoff relay R110 are thus energized, the line relay R120 is held operated and the cutoff relay R110 operates. Upon operating, the cutoff relay R110 interrupts, at the contacts 111 and 115, points in the original bridge circuit for energizing the upper winding of the line relay R120, thereby to free the line conductors C151 and C152 of the subscriber line 150 of impedance elements. Finally, the cutoff relay R110 interrupts, at the contacts 116, the previously mentioned path for applying ground potential to the start conductor C190 extending into the distributor 103. When ground potential is removed from the start conductor C190 the distributor 103 operates to preselect an idle link in the group of links to be assigned to the use of the next calling subscriber line. When the finder 101 seizes the calling subscriber line 150 the connector 102 operates to condition the Strowger mechanism therein to be responsive to dialed digits.

The subscriber at the substation A then dials the first digit of the directory number of the called substation C at the dial mechanism thereat, thereby to transmit a first series of impulses over the loop circuit extending by way of the subscriber line 150 between the substation A and the connector 102. Impulse-responsive apparatus in the connector 102 operates in response to a first series of impulses in order to cause the wipers 183, 184 and 185 of the Strowger mechanism included therein to be moved in the vertical direction to the level in the contact bank thereof, wherein the called subscriber line 160 is terminated. The subscriber at the substation A then dials the second digit of the directory number of the called substation C at the dial mechanism thereat, thereby to transmit a second series of impulses by way of the previously mentioned loop

circuit to the connector 102 in order to cause the wipers noted of the Strowger mechanism included therein to be moved in the rotary direction to the position of the contact set in the contact bank thereof, wherein the called subscriber line 160 is terminated. The subscriber at the substation A then dials the third digit of the directory number of the called substation C at the dial mechanism thereat, thereby to transmit a third series of impulses by way of the previously mentioned loop circuit to the connector 102 in order to cause the connector to select a corresponding code ringing current to be projected over the called subscriber line 160 in the event it is idle.

At this time, the wipers 183 and 185 engage the contacts in the contact bank terminating the line conductors C161 and C162, respectively, of the called subscriber line 160; and the wiper 184 engages the contact in the contact bank terminating the control conductor C164 of the called subscriber line 160. At this time, ground potential appears upon the control conductor C164 in the event the called subscriber line 160 is busy. On the other hand, battery potential appears upon the control conductor C164 in the event the called subscriber line 160 is idle.

Assuming that the called subscriber line 160 is busy, ground potential derived in the line circuit 105 individually associated therewith appears upon the control conductor C164 thereof, thereby to complete a path for energizing a busy relay included in the connector 102, which busy relay operates to cause busy tone current to be returned over the previously mentioned loop circuit including the calling subscriber line 150 extending to the substation A, in the usual manner. The production of busy tone in the receiver of the telephone instrument at the calling substation A indicates to the subscriber thereat that the desired connection cannot immediately be had due to the busy condition of the called subscriber line 160. The subscriber at the calling substation A then releases the operated link 100 and the line circuit 104 by replacing the receiver of the telephone instrument at the substation A upon its associated switchhook. The exact manner in which these operated pieces of apparatus are released is described in detail hereinafter.

Assuming that the called subscriber line 160 is idle, battery potential appears upon the control conductor C164 thereof, this battery potential being derived in the line circuit 105 individually associated with the called subscriber line 160. The path for applying battery potential to the control conductor C164 of the subscriber line 160 extends from battery by way of the upper winding of the cutoff relay R140, the lower winding of the line relay R130, and the contacts 143 to the control conductor C164. This application of battery potential to the control conductor C164 completes a path for short-circuiting the busy relay included in the connector 102, thereby to cause the connector 102 to operate and project ringing current of the previously selected code over the called subscriber line 160, whereby the ringer at the called substation C is operated in a characteristic manner. This characteristic operation of the ringer at the called substation C indicates to the subscriber thereat that the substation C is the called substation. Also, a switchthrough relay in the connector 102 operates to apply direct ground potential to the wiper 184 of the Strowger mechanism therein. This application of ground potential to the wiper 184 completes a circuit for

energizing in series the lower winding of the line relay R130 and the upper winding of the cutoff relay R140, this circuit extending from the grounded wiper 184 by way of C164, the contacts 143, the lower winding of R130 and the upper winding of R140 to battery. When the lower winding of the line relay R130 and the upper winding of the cutoff relay R140 are thus energized, both of these relays operate. Upon operating, the cutoff relay R140 interrupts, at the contacts 141 and 145, points in an obvious bridge circuit for energizing the upper winding of the line relay R130, thereby to free the line conductors C161 and C162 of the subscriber line 160 of impedance elements. Also, the cutoff relay R140 interrupts, at the contacts 148, a point in an obvious path for applying ground potential to the start conductor C190. Upon operating, the line relay R130 completes, at the contacts 133, a priming circuit for energizing in series the upper and lower windings of the cutoff relay R140, this circuit extending from ground by way of the lower winding of R140, the contacts 133, the resistor 138 and the upper winding of R140 to battery. Finally, the line relay R130 completes, at the contacts 131 and 135, a connection between the grounded control conductor C164 of the subscriber line 160 and the control conductor C163 of the subscriber line 160 extending to the contact banks of the Strowger mechanisms included in the finders of the links having access thereto, thereby to mark the subscriber line 160 as busy to the finders of these links, this path extending from the grounded control conductor C164 by way of the contacts 135 and 131 to the control conductor C163. The subscriber at the substation C then answers the call by removing the receiver of the telephone instrument thereat from its associated switchhook, thereby to cause the connector 102 to operate in order to interrupt the projection of ringing current over the called subscriber line 160 and to complete an established communication connection between the calling subscriber line 150 and the called subscriber line 160 by way of the operated link 100.

Assuming that the release of this established connection is under the control of the last subscriber to replace the receiver of the telephone instrument at his substation upon its associated switchhook, when the last subscriber at one of the substations replaces the receiver of the telephone instrument thereat upon its associated switchhook, the operated link 100 is released in the usual manner, thereby to interrupt the established communication connection extending between the subscriber lines 150 and 160. When the link 100 is released, ground potential therein is removed from the wiper 181, thereby to interrupt the previously traced circuit for energizing in series the lower winding of the line relay R120 and the upper winding of the cutoff relay R110, thereby to cause the line relay R120 to restore immediately and the cutoff relay R110 to restore shortly thereafter, the cutoff relay R110 being rendered slow to release while the line relay R120 is operated, due to the completed priming circuit for energizing in series the upper and lower windings thereof, as previously noted. Upon restoring, the cutoff relay R110 prepares, at the contacts 111 and 115, points in the previously traced bridge circuit, including the subscriber line 150, for energizing the upper winding of the line relay R120. Also, upon restoring, the cutoff relay R110 completes, at the contacts 113, a path for applying battery potential to the control

conductor C154 of the subscriber line 150, thereby to mark the subscriber line 150 as idle to the Strowger mechanisms included in the connectors of the links having access thereto. This path extends from battery by way of the upper winding of the cutoff relay R110, the lower winding of the line relay R120 and the contacts 113 to the control conductor C154 of the subscriber line 150. At this time, the line circuit 104 is completely released.

Also, when the link 100 is released, ground potential therein is removed from the wiper 184, thereby to interrupt the previously traced circuit for energizing in series the lower winding of the line relay R130 and the upper winding of the cutoff relay R140, thereby to cause the line relay R130 to restore immediately and the cutoff relay R140 to restore shortly thereafter, the cutoff relay R140 being rendered slow to release while the line relay R130 is operated, due to the completed priming circuit for energizing in series the upper and lower windings thereof, as previously noted. Upon restoring, the cutoff relay R140 prepares, at the contacts 141 and 145, points in the previously mentioned bridge circuit, including the subscriber line 160, for energizing the upper winding of the line relay R130. Also, upon restoring the cutoff relay R140 completes, at the contacts 143, the previously traced path for applying battery potential to the control conductor C164 of the subscriber line 160, thereby to mark the subscriber line 160 as idle to the Strowger mechanisms included in the connectors of the links having access thereto. At this time, the line circuit 105 is completely released.

In view of the above description of the mode of operation of the apparatus to extend a call from the substation A to the substation C, it will be understood that the apparatus is operative, in a substantially identical manner, to extend a call from the substation A to the substation D, from the substation B to the substations C or D, from the substation C to the substations A or B and from the substation D to the substations A or B.

A reverting call which is to be extended from the substation A to the substation B is first initiated at the substation A by removing the receiver of the telephone instrument thereat from its associated switchhook, thereby to complete the previously traced bridge circuit for energizing the upper winding of the line relay R120. When thus energized, the line relay R120 operates in order to cause battery potential to be applied to the control conductor C153 of the subscriber line 150 and ground potential to be applied to the start conductor C190; and to complete the previously traced priming circuit for energizing in series the upper and lower windings of the cutoff relay R110, in the manner previously explained. This application of ground potential to the start conductor C190 causes the distributor 103 to operate and assign a previously selected idle link in the group of links to the use of the calling subscriber line 150, in the manner previously explained. Assuming that the link 100 illustrated is assigned to the use of the calling subscriber line 150, this application of ground potential to the start conductor C190 and this application of battery potential to the control conductor C153 of the subscriber line 150 marks the position of the contact set in the contact bank of the Strowger mechanism included in the finder 101, wherein the subscriber line 150 is terminated. The finder 101 then operates in the previously described manner, thereby to seize the calling

subscriber line 150. When the subscriber line 150 is seized the cutoff relay R110 operates in order to mark the subscriber line 150 as busy to the Strowger mechanism included in the connectors of the links having access thereto, whereupon the line circuit 104 is completely operated, as previously explained.

The connector 102 is conditioned to be responsive to a series of dialed digits at this time. The subscriber at the substation A then dials at the dial mechanism thereat successively two predetermined digits into the connector 102, thereby to cause the connector 102 to operate and select the first trunk line terminating thereat to which an idle reverting call switch is connected. When these two predetermined digits are successively dialed the connector 102 operates as a trunk hunting connector in order to select a trunk line associated with an idle one of the reverting call switches or to return busy tone current over the loop circuit extending to the calling substation A in the event all of the reverting call switches are busy. Assuming that the reverting call switch 200 illustrated is the first idle switch, the connector 102 operates to seize the trunk line 170 extending thereto. The reverting call switch 200 is marked as idle or busy, respectively, by the presence of battery or ground potentials upon the control conductor C172 of the trunk line 170. At this time, the reverting call switch 200 being idle, battery potential appears upon the control conductor C172 of the trunk line 170, the path for applying battery potential to the control conductor C172 extending from battery by way of the resistor 206 and the contacts 271, 241 and 256 to the control conductor C172. When the connector 102 selects the trunk line 170, further operation thereof is arrested due to the presence of battery potential upon the control conductor C172 of the trunk line 170, in the usual manner.

When the trunk line 170 is thus seized by the connector 102, this connector operates to complete a loop circuit between the calling substation A and the line relay R230 in the reverting call switch 200, this loop circuit extending from ground by way of the lower winding of R230 and the contacts 226 to the line conductor C173 of the trunk line 170, and from battery by way of the upper winding of R230 and the contacts 221 to the line conductor C171 of the trunk line 170, the line conductors C171 and C173 of the trunk line 170 being connected by way of the operated link 100 to the line conductors C151 and C152, respectively, of the calling subscriber line 150, and the telephone instrument at the substation A being included in the previously traced bridge path extending between the line conductors C151 and C152 of the subscriber line 150. When thus energized, the line relay R230 operates to complete, at the contacts 231, an obvious circuit for energizing the winding of the hold relay R240. When thus energized, the hold relay R240 operates to complete, at the contacts 242, a path for applying ground potential to the control conductor C172 of the trunk line 170, this path extending from ground by way of the contacts 242 and 256 to the control conductor C172. This application of ground potential to the control conductor C172 of the trunk line 170 marks this trunk line as busy to the Strowger mechanisms included in the connectors of the links having access thereto and causes the switch-through relay in the connector 102 to operate. When the switch-through relay in the connector 102 operates, ground potential in the operated

link 100 is removed from the wipers 181 and 184 of the finder and connector 101 and 102, respectively, the link 100 and the line circuit 104 being retained in their operated positions at this time, due to the application of ground potential to the control conductor C172 of the trunk line 170 in the reverting call switch 200.

The subscriber at the calling substation A then dials at the dial mechanism thereat a third digit corresponding to the last digit of the directory number of the calling substation A, thereby to transmit a series of impulses by way of the previously mentioned loop circuit to the line relay R230. The line relay R230 follows the dialed impulses in the usual manner, restoring each time the loop circuit is interrupted and operating each time the loop circuit is completed. Each time the line relay R230 restores it interrupts, at the contacts 231, the previously mentioned circuit for energizing the winding of the hold relay R240, and completes, at the contacts 232, a circuit for energizing in multiple the winding of the control relay R250 and the rotary magnet M236 of the minor switch 280. The last-mentioned circuit extends from ground by way of the contacts 232 and 244 to the contacts 263, from the contacts 263 by way of the winding of R250 to battery; and from the contacts 263 by way of the contacts 274 and the rotary magnet M236 to battery. The hold relay R230 and the control relay R250 being of the slow-to-release type, remain operated during impulsing. Each time the circuit for energizing the rotary magnet M236 is completed this magnet operates to drive the wipers 283 and 285 of the minor switch 280 one step in the clockwise direction away from their normal positions. When the wipers noted of the minor switch 280 are driven away from their normal positions the set of switch springs S234 is actuated into engagement, thereby to prepare a circuit traced hereinafter for energizing the winding of the transfer relay R270, this circuit being interrupted at this time, at the contacts 251, by the operated control relay R250. In response to the third digit, the wipers 283 and 285 of the minor switch 280 are driven a number of steps away from their normal positions corresponding to the digit dialed, and into engagement with corresponding contacts in the associated contact banks 284 and 286, respectively. At the conclusion of the third digit, the line relay R230 reoperates, thereby to interrupt, at the contacts 232, the previously traced multiple circuit for energizing the winding of the control relay R250 and the rotary magnet M236, whereupon the control relay R250 restores shortly thereafter, and further operation of the rotary magnet M236 is arrested. Upon restoring, the control relay R250 completes, at the contacts 251, the previously mentioned circuit for energizing the winding of the transfer relay R270, this circuit extending from ground by way of the set of switch springs S234, the contacts 251 and the winding of R270 to battery. When thus energized, the transfer relay R270 operates to complete, at the contacts 272, an obvious holding circuit for energizing the winding thereof, and prepares, at the contacts 273, a multiple circuit traced hereinafter for energizing the winding of the control relay R250 and the rotary magnet M238 of the minor switch 290.

The subscriber at the calling substation A then dials at the dial mechanism thereat a fourth digit corresponding to the last digit of the directory number of the called substation B, thereby to

transmit another series of impulses by way of the previously mentioned loop circuit to the line relay R230. The line relay R230 follows the dialed impulses in the usual manner, restoring each time the loop circuit is interrupted and operating each time the loop circuit is completed. Each time the line relay R230 restores it interrupts, at the contacts 231, the previously mentioned circuit for energizing the winding of the hold relay R240, and completes, at the contacts 232, the previously mentioned circuit for energizing in multiple the winding of the control relay R250 and the rotary magnet M238 of the minor switch 290. The last-mentioned circuit extends from ground by way of the contacts 232 and 244 to the contact 263, from the contact 263 by way of the winding of R250 to battery; and from the contact 263 by way of the contact 273 and the rotary magnet M238 to battery. Each time the circuit for energizing the rotary magnet M238 is completed, this magnet operates to drive the wipers 293 and 295 of the minor switch 290 one step in the clockwise direction away from their normal positions. When the wipers noted of the minor switch 290 are driven away from their normal positions, the set of switch springs S235 is actuated, thereby to prepare a circuit traced hereinafter for energizing the winding of the transfer relay R260, this circuit being interrupted at this time, at the contacts 252, by the operated control relay R250. In response to the fourth digit, the wipers 293 and 295 of the minor switch 290 are driven a number of steps away from their normal positions corresponding to the digit dialed, and into engagement with corresponding contacts in the associated contact banks 294 and 296, respectively. At the conclusion of the fourth digit, the line relay R230 reoperates, thereby to interrupt, at the contacts 232, the previously traced circuit for energizing in multiple the winding of the control relay R250 and the rotary magnet M238 in order to cause the control relay R250 to restore shortly thereafter and to arrest further operation of the rotary magnet M238. Upon restoring, the control relay R250 completes, at the contacts 252, the previously mentioned circuit for energizing the winding of the transfer relay R260, this circuit extending from ground by way of the set of switch springs S235, the contacts 252 and the winding of R260 to battery. When thus energized, the transfer relay R260 operates to complete, at the contacts 261, an obvious holding circuit for energizing the winding thereof.

Shortly following the conclusion of the fourth digit dialed at the substation A, the subscriber thereat replaces the receiver of the telephone instrument thereat upon its associated switchhook, thereby to interrupt the previously mentioned loop circuit for energizing in series the upper and lower windings of the line relay R230, whereupon the latter relay restores. Upon restoring, the line relay R230 completes, at the contacts 232, a circuit for energizing the winding of the control relay R210, this circuit extending from ground by way of the contacts 232, 244, 262 and 258 and the winding of R210 to battery. When thus energized, the control relay R210 operates to complete, at the contacts 211, an obvious path for applying ground potential to the ringing machine start lead C206, to complete, at the contacts 212, an obvious path for applying battery potential by way of the winding of the switch-through relay R220 to the ring pickup lead C215, and to complete, at the contacts 214, an obvious holding circuit for energizing the winding of the hold relay

R240. The hold relay R240 being of the slow-to-release type, does not immediately restore, incident to the restoration of the line relay R230, and is retained in its operated position due to the completion of the previously mentioned holding circuit for energizing the winding thereof. Accordingly, ground potential is not removed from the control conductor C172 of the trunk line 170 at this time.

10 Shortly thereafter and at the beginning of a code ringing cycle, ground potential is applied in the ringing machine to the ring pickup lead C215, thereby to complete a circuit for energizing the winding of the switch-through relay R220, this circuit extending from the grounded ring pickup lead C215 by way of the contacts 213 and 224 and the winding of R220 to battery. When thus energized, the switch-through relay operates to complete, at the contacts 223, a holding circuit for energizing the winding thereof, this circuit extending from ground by way of the contacts 212 and 223 and the winding of R220 to battery. Also, the switch-through relay prepares, at the contacts 222 and 225, points in a circuit traced hereinafter for projecting ringing current from the ringing machine associated with the trunk 206' by way of the operated reverting call switch 200, the trunk line 170 and the link 100 over the subscriber line 150, the exact circuit for projecting ringing current from the ringing machine associated with the trunk 206' over the subscriber line 150, depending upon the positions of the wipers of the minor switches 280 and 290, in a manner more fully described subsequently.

35 As previously noted, a divided ringing circuit is employed in the system, a first group of substations associated with each party subscriber line having ringers thereat connected between one line conductor of the party line and ground, and a second group of substations associated with each party subscriber line having ringers thereat connected between the other line conductor of the party line and ground. Accordingly, the operation of the reverting call switch 200 depends upon whether the calling and called substations A and B are in the same group. In the event the substations A and B are in the same group, the reverting call switch 200 operates to cause ringing current of the code corresponding to the called substation B to be projected over the line conductor of the subscriber line 150 to which the ringers at each of the substations A and B are connected. On the other hand, in the event the substations A and B are in different groups, the reverting call switch 200 operates first to cause ringing current of the code corresponding to the called substation B to be projected over the line conductor of the subscriber line 150 to which the ringer at the called substation B is connected, and then to cause ringing current of the code corresponding to the calling substation A to be projected over the line conductor of the subscriber line 150 to which the ringer at the calling substation A is connected.

60 65 70 75 Also, it is noted that the substations associated with the subscriber line 150 and having ringers connected to one line conductor thereof are assigned directory numbers comprising a third odd digit; and the substations associated with the subscriber line 150 and having ringers connected to the other line conductor thereof are assigned directory numbers comprising a third even digit. Assuming that the third digit of the directory number of the calling substation A is the No. 1, and the third digit of the directory number of

the called substation B is the No. 3, the wipers noted of the minor switch 280 engage the first contacts in the associated contact banks, and the wipers noted of the minor switch 290 engage the third contacts in the associated contact banks. At this time, a circuit is completed for projecting ringing current of the code corresponding to the called substation B over the subscriber line 150, this circuit extending from the ungrounded terminal of the ringing machine winding by way of the ringing conductor M3, the third contact in the contact bank 294 and the associated wiper 293 of the minor switch 290, the upper winding of the ring cutoff relay R255 and the contacts 222 to the line conductor C171 of the trunk line 170, and therefrom by way of the operated link 100, the line conductor C151 of the subscriber line 150, and a condenser and the ringer at the called substation B to ground. Also, a circuit is prepared for energizing the upper winding of the ring cutoff relay R255 which is completed when the subscriber at the substation B answers the call by removing the receiver of the telephone instrument thereat from its associated switchhook, this circuit extending, when completed, by way of the previously traced path to the line conductor C151 of the subscriber line 150, and therefrom by way of the bridge path at the substation B between the line conductors C151 and C152 of the subscriber line 150, the line conductor C152 of the subscriber line 150, the operated link 100, the line conductor C173 of the trunk line 170, the contacts 225 and the windings 202 and 203 of the transformer 201 to ground.

Assuming that the third digit of the directory number of the calling substation A is the No. 2 and the third digit of the directory number of the called substation B is the No. 4, the wipers noted of the minor switch 280 engage the second contacts in the associated contact banks, and the wipers noted of the minor switch 290 engage the fourth contacts in the associated contact banks. At this time, a circuit is completed for projecting ringing current of the code corresponding to the called substation B over the subscriber line 150, this circuit extending from the ungrounded terminal of the ringing machine winding by way of the ringing conductor M4, the fourth contact in the contact bank 296 and the associated wiper 295 of the minor switch 290, the windings 205 and 204 of the transformer 201 and the contacts 227 to ground. The ringing current traversing the windings 204 and 205 of the transformer 201 induces a corresponding ringing current in the windings 202 and 203 thereof, which traverses a path extending from ground by way of the windings 203 and 202 of the transformer 201, and the contacts 225 to the line conductor C173 of the trunk line 170; and therefrom by way of the operated link 100, the line conductor C152 of the subscriber line 150 and the condenser and the ringer at the called substation B to ground. Also, a circuit is prepared for energizing the upper winding of the cutoff relay R255 which is completed when the subscriber at the called substation B answers the call by removing the receiver of the telephone instrument thereat from its associated switchhook, this circuit extending, when completed, from battery by way of the resistor 207, the second contact in the contact bank 284 and the associated wiper 283 of the minor switch 280, the fourth contact in the contact bank 294 of the associated wiper 293 of the minor switch 290, the upper winding of R255, the contacts 222, the line conductor C171 of the trunk line 170 and the

operated link 100 to the line conductor C151 of the subscriber line 150; and therefrom by way of the bridge path at the substation B between the line conductors C151 and C152 of the subscriber line 150 and a portion of the previously traced circuit to ground at the winding 203 of the transformer 201.

Assuming that the third digit of the directory number of the calling substation A is the No. 1 and the third digit of the directory number of the called substation B is the No. 2, the wipers noted of the minor switch 280 engage the first contacts in the associated contact banks, and the wipers noted of the minor switch 290 engage the second contacts in the associated contact banks. At this time, a circuit is completed for projecting ringing current of the code corresponding to the called substation B over the subscriber line 150, this circuit extending from the ungrounded terminal of the ringing machine winding by way of the ringing conductor M2, the second contact in the contact bank 296 and the associated wiper 295 of the minor switch 290, the windings 205 and 204 of the transformer 201 and the contacts 227 to ground. This ringing current traversing the windings 204 and 205 of the transformer 201 induces a corresponding ringing current in the windings 202 and 203 thereof which is projected by way of the previously traced path over the line conductor C151 of the subscriber line 150 to ground at the ringer at the called substation B. Also, a circuit is completed for projecting ringing current of the code corresponding to the calling substation A over the subscriber line 150, this circuit extending from the ungrounded terminal of the ringing machine by way of the ringing conductor M1, the first contact in the contact bank 284 and the associated wiper 283 of the minor switch 280, the second contact in the contact bank 294 and the associated wiper 293 of the minor switch 290, the upper winding of the ring cutoff relay R255, the contacts 222, the line conductor C171 of the trunk line 170, the operated link 100, the line conductor C151 of the subscriber line 150 and the condenser and the ringer at the calling substation A to ground. The ringing machine operates to complete the circuits for applying ringing voltages to the ringing conductors M1 to M5, inclusive, sequentially, thereby to cause the ringer at the called substation B and the ringer at the calling substation A to be operated alternatively. Also, a circuit is prepared for energizing the upper winding of the ring cutoff relay R255, which is completed when the subscriber at the substation B answers the call by removing the receiver of the telephone instrument thereat from its associated switchhook, this circuit extending, when completed, from the ringing conductor M1 by way of the previously traced path to ground at the winding 203 of the transformer 201.

Assuming that the third digit of the directory number of the calling substation A is the No. 2 and the third digit of the directory number of the called substation B is the No. 1, the wipers noted of the minor switch 280 engage the second contacts in the associated contact banks and the wipers noted of the minor switch 290 engage the first contacts in the associated contact banks. At this time, a circuit is completed for projecting ringing current of the code corresponding to the called substation B over the subscriber line 150, this circuit extending from the ungrounded terminal of the ringing ma-

chine winding by way of the ringing conductor M1, the first contact in the contact bank 294 and the associated wiper 293 of the minor switch 290, the upper winding of R255 and a portion of the previously traced circuit, including the line conductor C151 of the subscriber line 150, to ground at the ringer at the called substation B. Also, a circuit is completed for projecting ringing current of the code corresponding to the calling substation A over the subscriber line 150, this circuit extending from the ungrounded terminal of the ringing machine winding by way of the ringing conductor M2, the second contact in the contact bank 286 and the associated wiper 285 of the minor switch 280, the first contact in the contact bank 296 and the associated wiper 295 of the minor switch 290, the windings 205 and 204 of the transformer 201 and the contacts 227 to ground. This ringing current traversing the windings 204 and 205 of the transformer 201 induces a corresponding ringing current in the windings 202 and 203 thereof, which is projected by way of the previously traced circuit including the line conductor C152 of the subscriber line 150 to ground at the ringer at the calling substation A. As previously noted, the ringers at the called and calling substations B and A, respectively, are operated alternatively. Also, a circuit is prepared for energizing the upper winding of the ring cutoff relay R255 which is completed when the subscriber at the substation B answers the call by removing the receiver of the telephone instrument thereat from its associated switchhook, this circuit extending, when completed, from the ringing conductor M1 by way of the previously traced path to ground at the winding 203 of the transformer 201.

When the subscriber at the called substation B answers the call, one of the previously traced circuits for energizing the upper winding of the ring cutoff relay R255 is completed, depending upon whether the calling and called substations A and B, respectively, are in the same or different groups, as previously noted. When thus energized, the ring cutoff relay R255 operates to complete, at the contacts 257, an obvious holding circuit for energizing the lower winding thereof, to interrupt, at the contacts 256, the previously traced path for applying ground potential to the control conductor C172 of the trunk line 170, and to interrupt, at the contacts 258, the previously traced circuit for energizing the winding of the control relay R210, thereby to cause the latter relay to restore. Upon restoring, the control relay R210 interrupts, at the contacts 211, the previously traced path for applying ground potential to the ringing machine start lead C206 in order to arrest further operation of the ringing machine associated with the reverting call switch 200, and interrupts, at the contacts 212, the previously traced holding circuit for energizing the winding of the switch-through relay R220 in order to cause the latter relay to restore. Also, the control relay R210 interrupts, at the contacts 214, the previously mentioned holding circuit for energizing the winding of the hold relay R240, thereby to cause the latter relay to restore shortly thereafter. Upon restoring, the hold relay R240 interrupts, at the contacts 243, the previously mentioned holding circuit for energizing the lower winding of the ring cutoff relay R255, thereby to cause the latter relay to restore shortly thereafter, the ring cutoff relay R255 being of the slow-to-release type. Also, the hold relay R240 completes,

at the contacts 246, a circuit for energizing the release magnet M239 of the minor switch 290, this circuit extending from ground by way of the contacts 246 and 264 and the release magnet M239 to battery. When thus energized, the release magnet M239 operates to release the wipers noted of the minor switch 290, thereby to cause these wipers to be returned to their normal positions. When the wipers noted of the minor switch 290 are returned to their normal positions, the set of switch springs S235 is actuated into disengagement, thereby to interrupt the previously mentioned holding circuit for energizing the winding of the transfer relay R260, whereupon the latter relay restores. Upon restoring, the transfer relay R260 interrupts, at the contacts 264, the previously traced circuit for energizing the release magnet M239, and completes, at the contacts 265, a circuit for energizing the release magnet M237, this circuit extending from ground by way of the contacts 265, 266 and 275 and the release magnet M237 to battery. When thus energized, the release magnet M237 operates to release the wipers noted of the minor switch 280, thereby to cause these wipers to be returned to their normal positions. When the wipers noted of the minor switch 280 are returned to their normal positions the set of switch springs S234 is actuated into disengagement, thereby to interrupt the previously mentioned holding circuit for energizing the winding of the transfer relay R270, whereupon the latter relay restores. Upon restoring, the transfer relay R270 interrupts, at the contacts 275, the previously traced circuit for energizing the release magnet M237. Upon restoring, the hold relay R240, the ring cutoff relay R255 and the transfer relay R270 complete, at the contacts 241, 256 and 271, respectively, the previously traced path for applying battery potential by way of the resistor 206 to the control conductor C172 of the trunk line 170, thereby to mark this trunk line as idle to the connectors of the links having access thereto. At this time, the reverting call switch 200 is completely released for further use. As previously explained, when the ring cutoff relay R255 in the reverting call switch 200 operates, ground potential is removed from the control conductor C172 of the trunk line 170, thereby to cause the operated link 100 to be released, whereupon the previously traced circuit for energizing in series the lower winding of the line relay R120 and the upper winding of the cutoff relay R110 in the line circuit 104 individually associated with the subscriber line 150 is interrupted. The line relay R120 immediately restores to complete, at the contacts 122 and 124, a bridge circuit for energizing in series the upper and lower windings of the cutoff relay R110, and to interrupt, at the contacts 123, the previously traced priming circuit for energizing in series the upper and lower windings of the cutoff relay R110. The bridge circuit for energizing in series the upper and lower windings of the cutoff relay R110 extends from ground by way of the lower winding of R110 and the contacts 124 to the line conductor C152 of the subscriber line 150, and from battery by way of the upper winding of R110 and the contacts 122 and 121 to the line conductor C151 of the subscriber line 150, a bridge connection being completed at the called substation B between the line conductors C151 and C152 of the subscriber line 150. Accordingly, the cutoff relay R110 remains in its operated position incident to the release

of the link 100 when the subscriber at the called substation B answers the reverting call upon the subscriber line 150. Also, upon restoring, the line relay R120 completes, at the contacts 126, an alternative path for applying ground potential to the control conductor C154 of the subscriber line 150, thereby to mark the subscriber line 150 as busy to the connector switches of the links having access thereto. This path extends from ground by way of the contacts 114 and 126 to the control conductor C154. Accordingly, at this time, the line circuit 104 individually associated with the subscriber line 150 is operated positively to lock the subscriber line 150 out of service; and talking battery is supplied by way of the previously traced bridge circuit to the telephone instrument at the called substation B.

As previously noted, when the subscriber at the called substation B answers the reverting call on the subscriber line 150, the reverting call switch 200 is released, thereby to interrupt the circuit for projecting ringing current over the subscriber line 150 in order to cause further operation of the ringer at the calling substation A to be arrested. When the operation of the ringer at the calling substation A is arrested the subscriber thereto is advised that the subscriber at the called substation B has answered the reverting call. The subscriber at the substation A then removes the receiver of the telephone instrument thereat from its associated switchhook, thereby to complete an established revertive connection between the calling and called substations A and B, respectively, for two-way communication therebetween, talking battery being supplied to the substation A by way of the previously traced bridge circuit.

The release of this established connection between the substations A and B is under the control of the last subscriber to replace the receiver of the telephone instrument at his substation upon its associated switchhook. When the last subscriber replaces the receiver of the telephone instrument at his substation upon its associated switchhook, the bridge circuit for energizing in series the upper and lower windings of the cutoff relay R110 is interrupted, thereby to cause the latter relay to restore. Upon restoring, the cutoff relay R110 completes, at the contacts 113, the previously traced path for applying battery potential by way of the upper winding of the cutoff relay R110 and the lower winding of the line relay R120 to the control conductor C154 of the subscriber line 150, thereby to mark the subscriber line 150 as idle to the connectors of the links having access thereto.

In view of the above description of the mode of operation of the apparatus to extend a reverting call from the substation A to the substation B, it will be understood that the apparatus is operative, in a substantially identical manner, to extend a reverting call from the substation B to the substation A, from the substation C to the substation D, and from the substation D to the substation C.

Also, it is noted that a timing arrangement is incorporated in the connector 102 which is operative in the event the switch-through relay therein does not operate within a predetermined time interval, due to the fact that the connector has not been fully operated to seize a line accessible thereto, to cause ground potential to be removed from the wiper 181. For example, the link 100 may be seized, in the previously described manner, by the appearance of a fault on

any one of the subscriber lines, in which case the connector 102 thereof will not be operated subsequently to seize a line accessible thereto, in order to cause the operation of the switch-through relay therein, whereby ground potential will be removed from the wiper 181, as previously noted. Under these conditions, when ground potential is removed from the wiper 181, the circuit for energizing in series the upper winding of the cutoff relay and the lower winding of the line relay in the line circuit individually associated with the line having the fault thereon is interrupted, thereby to cause the line relay therein to restore and the cutoff relay therein to remain operated. The operated cutoff relay in the line circuit individually associated with the line having the fault thereon causes the last-mentioned line to be locked out of service, in the manner previously explained, in connection with the extension of a reverting call between the substations A and B over the subscriber line 150. When the fault is removed from the line the bridge circuit for energizing in series the upper and lower windings of the cutoff relay in the line circuit individually associated therewith is interrupted, thereby to cause the cutoff relay to restore, whereupon the line is again marked as idle to the connectors of the links having access thereto.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. A line circuit adapted for use in a telephone system including a line accessible to automatic switching apparatus; said line circuit comprising a line relay, a cutoff relay, means responsive to the presence of a call on said line for causing operation of said line relay, means responsive to the seizure of said line when a call is thereon by said switching apparatus for retaining operated said line relay and for causing operation of said cutoff relay, means responsive to the release of said line by said switching apparatus for causing restoration of said line relay, means for retaining operated said cutoff relay subsequent to the release of said switching apparatus in the event a call remains on said line, and control circuits for said switching apparatus governed by said line relay and said cutoff relay.
2. A line circuit adapted for use in a telephone system including a line accessible to automatic switching apparatus; said line circuit comprising a line relay, a cut-off relay, means responsive to the presence of a call on said line for causing operation of said line relay, means controlled when said line relay is operated and said cutoff relay is restored for marking said line as a calling line to said switching apparatus, means responsive to the seizure of said line when a call is thereon by said switching apparatus for retaining operated said line relay and for causing operation of said cutoff relay, means controlled when said line relay and said cutoff relay are operated for marking said line as a busy called line to said switching apparatus, means responsive to the release of said line by said switching apparatus for causing restoration of said line relay, means for retaining operated said cutoff relay subsequent to the release of said switching apparatus in the event a call remains on said

line, means controlled when said line relay is restored and said cutoff relay is operated for marking said line as a busy locked-out line to said switching apparatus, and control circuits for said switching apparatus governed by said line relay and said cutoff relay.

3. A line circuit adapted for use in a telephone system including a line accessible to automatic switching apparatus; said line circuit comprising a line relay, a cutoff relay, means responsive to the presence of a call on said line for causing operation of said line relay, means controlled when said line relay is operated and said cutoff relay is restored for marking said line as a calling line to said switching apparatus and for causing said switching apparatus to seize said line, means responsive to the seizure of said line when a call is thereon by said switching apparatus for retaining operated said line relay and for causing operation of said cutoff relay, means controlled when said line relay and said cutoff relay are operated for marking said line as a busy called line to said switching apparatus, means for causing said switching apparatus to release said line, means responsive to the release of said line by said switching apparatus for causing restoration of said line relay, means for retaining operated said cutoff relay subsequent to the release of said switching apparatus in the event a call remains on said line, and means controlled when said line relay is restored and said cutoff relay is operated for marking said line as a busy locked-out line to said switching apparatus.

4. A line circuit adapted for use in a telephone system including a line accessible to automatic switching apparatus; said line circuit comprising a line relay, a cutoff relay, a control network including a series operating circuit for said line relay and said cutoff relay, means for causing said switching apparatus to seize said line as a calling line or as a called line, means controlled when said line is seized by said switching apparatus for completing said series operating circuit, and control circuits for said switching apparatus governed by said line relay and said cutoff relay.

5. A line circuit adapted for use in a telephone system including a subscriber line of the party type and automatic switching apparatus having access to said subscriber line; said line circuit comprising a line relay, a cutoff relay including two windings, a control network for selectively operating said line relay and said cutoff relay, control circuits for said switching apparatus governed by said line relay and said cutoff relay, whereby said switching apparatus is selectively controllable to extend a connection to a substation on said subscriber line and to extend a connection from a substation on said subscriber line and to extend a connection between two substations on said subscriber line, and a circuit including the two windings of said cutoff relay for supplying talking current to the two substations on said subscriber line when a connection is extended therebetween.

6. A line circuit adapted for use in a telephone system including a subscriber line of the party type and automatic switching apparatus having access to said subscriber line; said line circuit

consisting solely of a line relay, a cutoff relay, said relays being mechanically operative entirely independently of each other, a control network for selectively operating said line relay and said cutoff relay, and control circuits for said switching apparatus governed by said line relay and said cutoff relay, whereby said switching apparatus is selectively controllable to render to the substations on said line both calling and called services and also reverting call service.

5 7. A line circuit adapted for use in a telephone system including a line accessible to automatic switching apparatus; said line circuit comprising a line relay, a cutoff relay, a control network including a series operating circuit for said line relay and said cutoff relay, and control circuits for said switching apparatus governed by said line relay and said cutoff relay.

15 8. A line circuit adapted for use in a telephone system including a line accessible to automatic switching apparatus; said line circuit comprising a line relay; a cutoff relay; a control network including a series operating circuit for said line relay and said cutoff relay, an independent operating circuit for said line relay, and a holding circuit for said cutoff relay; and control circuits for said switching apparatus governed by said line relay and said cutoff relay.

20 9. A line circuit adapted for use in a telephone system including a line accessible to automatic switching apparatus; said line circuit comprising a line relay including first and second windings; a cutoff relay including first and second windings; a control network including a first operating circuit including the first winding of said line relay, a second operating circuit including in series the second winding of said line relay and the first winding of said cutoff relay, and a holding circuit including the second winding of 25 said cutoff relay; and control circuits for said switching apparatus governed by said line relay and said cutoff relay.

30 10. A line circuit adapted for use in a telephone system including a line accessible to automatic switching apparatus; said line circuit comprising a line relay including first and second

35 windings; a cutoff relay including first and second windings; a control network including a first operating circuit including the first winding of said line relay, a second operating circuit including in series the second winding of said line relay and the first winding of said cutoff relay, and a holding circuit including in series the first and the second windings of said cutoff relay; and control circuits for said switching apparatus governed by said line relay and said cutoff relay.

45 11. A line circuit adapted for use in a telephone system including a line accessible to automatic switching apparatus; a line relay including a winding; a cutoff relay including two windings; a control network including an operating circuit including the winding of said line relay, and two independent holding circuits each including in series the first and the second windings of said cutoff relay; and control circuits for 50 said switching apparatus governed by said line relay and said cutoff relay.

55 60 65
